UNITED STATES PATENT OFFICE.

JOHN M. WADDELL, OF ALEXANDRIA, LOUISIANA.

SAW-SHARPENING MACHINE.

No. 823,830.

Specification of Letters Patent.

Patented June 19, 1906.

Application filed October 20, 1904. Serial No. 239,253.

To all whom it may concern:

Be it known that I, JOHN M. WADDELL, a citizen of the United States, and a resident of Alexandria, in the parish of Rapides and State of Louisiana, have invented a new and Improved Saw-Sharpener Machine, of which the following is a full, clear, and exact description.

My invention relates to machines for sharpening saws, and is especially applicable to such gangs of saws as are employed in cotton-gins and the like.

The principal objects of the invention are to provide an apparatus by which each tooth will be of proper form and in which after the machine has been set the entire gang may be automatically operated upon.

Reference is to be had to the accompanying drawings, forming a part of this specification, in which similar characters of reference indicate corresponding parts in all the figures.

Figure 1 is a broken front elevation of one embodiment of my invention with parts in section. Fig. 2 is a vertical transverse section therethrough on the line 2-2 of Fig. 1. Fig. 3 is a similar view on the line 3-3 of Fig. 1. Fig. 4 is a detail showing a portion of the clutch-actuating mechanism. Fig. 5 is a broken top plan view. Fig. 6 is a vertical sectional detail through the side-grinding wheel. Fig. 7 is a similar view of a portion of the carriage-actuating mechanism. Fig. 8 is a side elevation, parts being broken away, of an eccentric for moving the wheels; and Fig. 9 is a central vertical section therethrough.

10 designates a frame, upon the vertical members of which are mounted brackets 11, and in these brackets is journaled a rotatable work support or shaft 12. This shaft carries a saw-cylinder 13, the saws 14 of which are to be sharpened, said cylinder being fixed in place by nuts 15, operating upon threaded portions of the shaft.

15 Upon upper horizontal members of the frame are carried suitable ways 16 to receive a table or carriage 17. Rising from the upper surface of this carriage is a substantially horizontal arm 18 overhanging the saws, at the outer end of which arm are provided vertical ways 19, upon which slides a head or carrier 20. In this head is journaled a horizontal shaft 21, having fast upon its inner end a throat-grinding wheel or gummier 22, here 25 shown as having its outer face vertical and its inner inclined at the edge at 23, so that it

will conform to the throat of the particular teeth upon which it is to operate. The working surface of this wheel may be of metal and cut after the manner of a file or may have 60 any other suitable reducing projections or dress. The shaft 21 is rotated by a pulley 24, connected by a belt 25 with a larger pulley 26, fixed upon a shaft 27, journaled in suitable bearings upon the upper surface of 65 the carriage. The shaft 27 also carries a pulley 28, from which a belt 29 extends to a larger pulley 30, mounted upon a longitudinal shaft 31, along which it may be moved by arms 32, depending from the under side of 70 the carriage, while it is constrained to rotate therewith by key mechanism which will be hereinafter described. Upon one extremity of the longitudinal shaft is carried a fast pulley 33, adjacent to which are two loose pulleys 34 and a fourth inner loose pulley 35. These pulleys are connected by belts 36 36^a with a wide pulley 37, rotatable with a shaft 38, journaled in standards 39 at the lower part of the frame. The shaft 38 also has fixed 80 upon it a pulley 40, which may be rotated from any convenient source of power by a belt 41.

The head is forced toward the work by a spring 42, interposed between it and a screw 85 43, threaded through the upper side of the head and having a hand-wheel by which it may be rotated to vary the tension. The shaft 21 is capable of some longitudinal movement in the head and is held normally inward 90 by a spring 44, interposed between the inner wall of a recess in which it is situated and a collar 45, fixed to the shaft. From the head, at each side of the saw which is being operated upon, depends a retaining projection 95 45^a, preventing the saw from springing sideways.

Pivoted at 46 upon the carriage is an arm or carrier 47, at the outer end of which, over the saws, are opposite branches 48 48. In 100 these branches are journaled alined shafts 49, having secured upon them side-grinding members or wheels 50, lying in parallel planes which intersect that of the throat-grinding wheel, being substantially at right 105 angles thereto. These side-grinding wheels have oppositely-inclined working edges 51 51. Each of the shafts 49 has fast upon it a bevel-pinion 52, which meshes with a bevel-gear 53, common to both and secured upon 110 the extremity of a shaft 54, journaled within the arm 47. The inner end of this shaft

carries a pulley 55, from which a belt 56 extends to a larger pulley 57 upon the shaft 27. One of the shafts 49 is hollow, and into this extends a projection 58 upon the other. 5 Between the shafts is interposed a spring 59, which forces them apart and the inclined edges of the wheels 50 into contact with the work. As the arm 46 is raised and lowered, as will be later described, it becomes desirable to first move the wheels away from the saws and then restore them to their normal position, in which the spring forces them against the work. To this end actuating members, here shown as bars 60, are mounted upon a bracket 61, projecting from the carriage and have two portions lying in different vertical planes with an intermediate inclined portion 62. They may be connected at their upper ends by a cross-bar 63. Secured upon each shaft at the inner side of its actuating-bar is a collar 64, having a rounded edge 65, which enables it to move readily over the inclined portion of its bar. When these collars are in contact with the lower portions of the bars, as illustrated in Fig. 1 of the drawings, the side-grinding wheels will be held by the spring against the edges of the saws to operate thereon; but when the saws are raised the rounded edges of the 25 collars at once contact with the inclined portions of the bars, moving the wheels toward one another and out of contact with the saws, they being maintained in this position until lowered by the upper portions of the bars, as 30 is shown in Fig. 6.

To permit the teeth to be successively advanced to be acted upon by the throat-grinding wheels, the supporting-shaft is provided with a sprocket-wheel 66, connected by a 40 chain 67 with a sprocket-wheel 68, fixed upon a short shaft 69. This shaft is rotated by worm-gearing 70 from a shaft 71, journaled transversely of the frame, which in turn is connected by worm-gearing 72 with the 45 shaft 31. The rotation imparted to the saws by this gearing is so slow that the throat-grinding wheel has ample opportunity to act, but any appreciable movement which occurs is taken up by the spring 44.

50 To enable the wheels to act upon the saws successively, the carriage is intermittently advanced a distance equal to the space between said saws by means of a shaft 73, journaled in brackets depending from the under side of the carriage and having at its outer extremities pinions 74, 74, meshing with racks 75, which extend along the upper members of the frame. Fixed to this shaft is a ratchet-wheel 76, having a coacting pawl 60 77, pivoted upon an arm 78, movable about the shaft 73. The pawl is provided with a rearward extension 79, in which is rotatably mounted a threaded rod 80, having a head 81, by which it may be turned. Upon the 65 rod moves a nut 82, to which is pivoted an

operating-rod 83. By turning the rod the position of the nut thereon, and consequently the throw imparted to the ratchet mechanism, may be varied. The relation of the pawl and its supporting-arm to the ratchet-wheel is such that a downward pull upon the operating-rod brings the pawl into coaction with the ratchet-teeth to rotate the wheel and shaft 73, and when the rod is moved upwardly the pawl swings away from the teeth against a stop member 83^a, carried by the arm, for a sufficient distance to disengage it and allow its rearward movement without disturbing the ratchet-wheel. The operating-rod is braced against lateral play by inclined members 84, extending from the under side of the carriage and meeting in a sleeve through which the rod moves and has at its lower end a strap 85, surrounding an eccentric 86, rotatable with the shaft 87. 75 At the same time the eccentric is permitted longitudinal movement on the shaft by means of a groove 88, extending along said shaft and having opposite it, in the eccentric, a recess 89, this groove-recess receiving 80 a set of balls 90, located partly in each and retained within the eccentric by side plates 91. The eccentric also has annular chambers 92, separated by a wall 93, in which operate sets of balls 94. By this expedient 95 the shaft and eccentric are compelled to rotate together, while very free longitudinal movement of the latter is permitted. The same method of mounting is also preferably applied to the pulley 31.

100 The shaft 87 is rotated by a gear 95, with which meshes a pinion 96 upon the shaft 38. To secure intermittent operation, the gear 95 is loose upon the shaft and carries one member 96^a of a jaw-clutch, the companion member 97 of which is keyed to the shaft for longitudinal movement by the ball device just described or any other suitable arrangement. With a groove in the member 97 coacts an arm 98 upon a lever 99, which is so held by a weight 100 that the clutch members are normally separated. Against the upper edge of one extremity of the lever 99 rests a lever 101, and with the opposite end of this last-named lever contacts a small lever 102, fulcrumed 105 upon the bracket 11. Fixed upon the work-supporting shaft is a pair of arms 103, 103, having between them a movable contact member or arm 104, which is forced against one of the arms in the direction of rotation of the work by a spring 105 and which will contact with the adjacent end of the lever 102, being permitted to slip by the same when its work has been completed by virtue of the spring. Secured upon the shaft 87 adjacent to the lever 101 is a disk 106, in which is a depression 107, which the end of the lever 99 may enter. Upon each rotation of the work-support its contact projection coacts with the lever system and first moves the lever 99 out of the 110 120 125 130

disk-depression and then brings the clutch members into engagement. The shaft 87 at once begins its rotation, moving the depression away from the lever 99, and thus locking the clutch members before the contact projection leaves the lever 102, maintaining the engagement for a complete rotation of the shaft 87. The resultant throw of the eccentric is sufficient to advance the carriage 10 through the ratchet mechanism an amount equal to the distance between adjacent saws. When this travel and the rotation of the shaft 87 have been completed, the depression 107 reaches the lever 99, which enters it, separating the clutch members and stopping the movement of the carriage at the proper point.

Before shifting the carriage the grinding-wheels must be moved from the saw-teeth to allow this, and for this purpose the rod 83 has attached to it an arm 108, which is connected by a link 109 with a lever 110, conveniently fulcrumed upon the fixed arm 18. One arm 111 of this lever extends beneath a cross-bar of the head, while a second arm 112 is connected by a link 113 with the arm 48. The ratios of the arms of the levers are such that before the carriage is moved along the work the wheels are lifted from the saws, the movement being sufficient to also clear the retaining projections 45^a. To limit the downward movement of the wheels, a stop member is preferably provided, which is here shown as a block 114, which may be of copper and which preferably contains a soft-metal filling 115 for contact with the saw-teeth. This block is supported by a link 116, pivoted to a projection 116^a upon the block and to the arm 111 of the lever and is retained against movement circumferentially of the saw by a link 117, pivoted to the carriage. With the projection of the stop member will contact a roll 118, carried upon a stud at the end of the shaft of the throat-grinding wheel and be held from moving too far downwardly. The relation of the wheel to the saws may be varied by suitable screws, which adjust the position of a bar 119 upon which the projection 116^a is supported.

Means must also be provided for raising the throat-grinding wheel from the saw upon the advance of each tooth. This is here shown as consisting of a shaft 120, journaled in the arm 18 and having at its outer end an arm 121, preferably rounded at its outer extremity and contacting with the head to raise it upon the ways independently of the lever 110. The opposite end of the shaft 120 has fast upon it a crank 122, to which is articulated a rod 123, terminating in a strap 124. This strap surrounds an eccentric 125, carried by the shaft 27, the throw of which eccentric is sufficient to raise the throat-grinding wheel out of the tooth.

When the carriage reaches the end of its travel or after the last saw has been operated

upon, it contacts with a lever 126, fulcrumed upon the frame and connected by a rod 127 with a lever 128, mounted at the opposite end of the frame. This portion of the rod carries a belt-shifting bar 129, having a pair of projections 130 130, situated at each side of the belt 36 and a third projection 131 at the outer side of the belt 36^a. The loose pulley 35 has upon its hub a bevel-gear 132, meshing with a similar gear 133 fast upon a shaft 134, journaled transversely of the frame. This shaft also has fixed upon it a sprocket-wheel 135 over which and over sprocket-wheels 136 rotatable upon the frame, passes a chain 137, which is connected at its opposite ends to the carriage. The contact of the carriage with the lever 126, operating through the belt-shifter, moves the belts 36 and 36^a, so that they engage the loose pulleys 34 and 35. The latter, by the rotation of the bevel-gearing and the consequent pull of the chain, draws the carriage back to the starting-point. Here it strikes the lever 128, when the inner projection 130 will move the belt 36 from the pulley 35 to the pulley 34, leaving the belt 36^a upon the companion pulley 34, and thus stopping the machine.

In using the machine the gang of saws to be sharpened is placed upon the work-support and the grinding-wheels adjusted to properly operate thereon. The belt 36^a is then moved by hand or otherwise upon the tight pulley 33, which through the interposed gearing rotates the grinding-wheels. The gumer operates about the entire periphery of the first saw and is then raised and automatically transferred to the second. As this continues the side-grinding wheels come into operation and complete the sharpening, they moving from saw to saw with the gumer. After the entire gang has been completed the carriage is automatically returned to its initial point and stopped in readiness to repeat its work. It will be seen that not only is the sharpening carried out without manual intervention, but each tooth has imparted to it a correct contour, in which the throat presents a square operating-surface, which will give the maximum strength, enabling it to pull off the lint without cutting.

Having thus described my invention, I claim as new and desire to secure by Letters Patent—

1. A saw-sharpening machine comprising a rotatable work-support, a plurality of side-grinding wheels and a throat-grinding wheel, a single means for simultaneously moving each of the grinding-wheels toward and from the work-support, means for simultaneously moving all of the grinding-wheels longitudinally of the work-support at the end of a complete rotation of said support, and means controlled by the rotation of the work-support for actuating said last-named means.

2. A saw-sharpening means comprising a

rotatable work-support, a movable grinding member, means for moving the grinding member toward and from the work and means on the work-support for controlling said movements.

3. A saw-sharpening machine comprising a rotatable work-support, a movable grinding member, means controlled by the movement of the work-support for moving the grinding member toward and from the work, and means for fixing the position of the grinding member after its movement.

4. A saw-sharpening machine comprising a side - grinding member, a throat - grinding member, means for simultaneously moving said grinding members from the work, and independent means for moving the throat-grinding member.

5. In a saw-sharpening machine, the combination of a rotatable work-support, a carriage, a plurality of side-grinding wheels rotatable in bearings movably mounted upon the carriage, means for simultaneously moving the bearings to and from the work-support, and means controlled by the rotation of the work-support for moving the carriage longitudinally thereof at the end of a complete rotation of the said support.

6. In a saw-sharpening machine, the combination with a work-support, of a carriage provided with ways and movable longitudinally of the work-support, a head sliding upon the ways, a shaft journaled in the head, a grinding-wheel carried by the shaft, means for intermittently moving the head in the ways, and means having a lost-motion connection with the head for limiting the movement thereof in the direction of the support.

7. In a saw-sharpening machine, the combination with a rotatable work-support, of a carriage provided with ways and movable longitudinally of the support, a head sliding upon the ways toward and from the support, a shaft journaled in the head, a grinding-wheel carried by the shaft, means for moving the head upon the advance of each tooth of the saw, means for moving the carriage at the end of a complete rotation of the work-support, and means whereby the rotation of the work-support may control said carriage-moving means.

8. In a saw-sharpening machine, the combination with a rotatable support adapted to receive a plurality of saws, of a traveling carriage provided with ways, a head sliding upon the ways, a shaft journaled in the head, a grinding-wheel carried by the shaft, continuously-rotatable means for moving the head upon the advance of each tooth of the saw, and intermittently-operating means for moving said head for each rotation of the saws.

9. In a saw-sharpening machine, the combination with a work-support, of a carriage provided with ways, a head sliding upon the

ways, a shaft journaled in the head, a grinding-wheel carried by the shaft, means for moving the head, a member for limiting the movement of the head, a link connecting said limiting member with the carriage and a lost-motion connection between the head and the moving means.

10. In a saw-sharpening machine, the combination with a work-support, of a carriage, a carrier movable upon the carriage, a shaft journaled in the carrier and longitudinally movable therethrough, a grinding-wheel fixed to the shaft, a collar carried by the shaft, and an actuating member projecting from the carriage and with which the collar contacts.

11. In a saw-sharpening machine, the combination with a work-support, of a carriage, a carrier movable upon the carriage, a shaft journaled in the carrier and longitudinally movable therethrough, a grinding-wheel fixed to the shaft, a collar carried by the shaft, and an actuating member projecting from the carriage, and with which the collar contacts, said actuating member having contact-faces lying in different planes.

12. In a saw-sharpening machine, the combination with a work-support, of a carriage, a carrier movable upon the carriage, alined shafts journaled in the carrier and longitudinally movable therethrough, tension means for effecting the movement of the shafts, and grinding-wheels fixed to the shafts.

13. In a saw-sharpening machine, the combination with a work-support, of a carriage, a carrier movable upon the carriage, alined shafts journaled in the carrier and longitudinally movable therethrough, grinding-wheels fixed to the shafts, and means for forcing the shafts apart.

14. In a saw-sharpening machine, the combination with a work-support, of a carriage, a carrier movable upon the carriage, alined shafts journaled in the carrier and longitudinally movable therethrough, automatic means for effecting the movement, and a spring interposed between the shafts.

15. In a saw-sharpening machine, the combination with a work-supporting shaft, of a carriage, a grinding member mounted upon the carriage, a driving-shaft, a loose pulley on the driving-shaft, a connection between the loose pulley and the carriage, a power-shaft and means whereby the power-shaft and the loose pulley may be connected and disconnected by the movement of the carriage.

16. In a saw-sharpening machine, the combination with a work-supporting shaft, of a carriage, a grinding member mounted upon the carriage, a driving-shaft, a loose pulley thereon, gearing associated with the loose pulley, a chain connecting the gearing and the carriage, a power-shaft, and means whereby the power-shaft and the loose pul-

ley may be connected and disconnected by the movement of the carriage.

17. In a saw-sharpening machine, the combination with a work-supporting shaft, of a carriage, a grinding member mounted upon the carriage, a driving-shaft, fast and loose pulleys thereon, connections between the loose pulley and the carriage, a power-shaft, a belt connecting the power-shaft and the loose pulley, a belt-shifter associated with the belt for shifting the same to the fast pulley, and means whereby the belt-shifter may be operated by the movement of the carriage.

18. In a saw-sharpening machine, the combination with a work-supporting shaft, of a carriage, a grinding member mounted upon the carriage, a driving-shaft, a fast pulley and a plurality of loose pulleys thereon, connections between one of the loose pulleys and the carriage, a power-shaft, belts connecting the power-shaft and the pulleys, a belt-shifter associated with the belts and having a plurality of projections adjacent to the pulley to which the carriage is connected, and a single projection adjacent to the fast pulley and means whereby the belt-shifter may be operated by the movement of the carriage.

19. In a saw-sharpening machine, the combination with a rotatable work-support, of a movable grinding member, a shaft from

which the grinding member is moved, a clutch controlling the rotation of the shaft, and means for operating the clutch by the work-support.

20. In a saw-sharpening machine, the combination with a rotatable work-support, of a movable grinding member, a shaft from which the grinding member is moved, a clutch controlling the rotation of the shaft; means for effecting an engagement of the clutch by the movement of the work-support, and gravity-actuated means for releasing the clutch.

21. In a saw-sharpening machine, the combination with a rotatable work-support, of a movable grinding member, a shaft from which the grinding member is moved, a clutch controlling the rotation of the shaft, means for effecting an engagement of the clutch by the work-support, gravity-actuated means for releasing the clutch, and means rotatable with the clutch for controlling its movement.

In testimony whereof I have signed my name to this specification in the presence of two subscribing witnesses.

JOHN M. WADDELL.
